UNITED STATES PATENT OFFICE

2,656,879

DESK ARM BRACE

Arthur P. Brashear, Jr., Temple, Tex., assignor
to American Desk Manufacturing Company,
Temple, Tex., a corporation of Texas

Application April 9, 1951, Serial No. 220,060

4 Claims. (Cl. 155—125)

1

This invention relates to furniture construction and more particularly to a combined chair and desk of the type generally used in schools wherein a desk arm is supported on one side of the chair and overlies a portion of the seat member.

The primary object of this invention is to provide a new and useful brace for the desk arm of the combined chair and desk construction described hereinabove which allows for ready vertical adjustment of the chair or desk arm.

A further object of this invention is to provide a device of the character described wherein the construction is such that the brace is free from projections that might damage clothing.

A further object of this invention is to provide a device of the character described in which the brace supporting the desk arm is provided with a means for effecting a tight and noiseless connection with the extended portion of one of the rear legs of the chair.

Yet another object of this invention is to provide a device of the character described which is relatively simple in design and construction, inexpensive, easy to manipulate to effect the vertical adjustments, and very efficient for its intended purpose.

These, together with various ancillary objects and features of the invention which will later become apparent as the following description proceeds, are attained by the device, a preferred embodiment of which has been illustrated by way of example only in the accompanying drawings, wherein:

Figure 1 is a perspective view of the invention shown in position on a chair;

Figure 2 is a side elevational view of the invention and illustrating different vertical positions;

Figure 3 is fragmentary enlarged side elevational view of the invention illustrating the manner of securing the brace to the chair; and

Figure 4 is a sectional view taken substantially on the plane of section line 4—4 of Figure 3.

Specific reference is now made to the drawings. In the several views in the accompanying drawings and in the following specification reference characters indicate corresponding elements throughout.

Indicated generally at 10 is a chair having front legs 12 and rear legs 14 supporting a seat member 16, the rear legs being extended as at 18 to support a backrest 20. It is preferred that the front and rear legs as well as the extensions 18 be constructed of angles.

2

The present invention is in the form of a vertically adjustable brace and is indicated at 22. The brace is constructed of an elongated bar 24, also preferably of angle construction, which bar includes a forward portion 26 and a downwardly inclined rear portion 28. Integral with or secured to the vertical flange of the forward portion 26 is a horizontal bar 30 which, together with the forward portion 26, serves as a means to secure a conventional desk arm (not shown).

A means is provided for securing in vertically adjusted positions the forward portion 26 to one of the front legs 12. This means can take various forms and the one illustrated in the drawings comprises an angle bar 32 depending from the forward portion 26, this bar partially embracing the upwardly extended portion 34 of one of the front legs 12. The front leg 12 and extended portion 34 are also of angle construction and are provided with vertically spaced apertures 36 adjacent the top and bottom of the front leg. Angle lugs 38 are provided and appropriate bolts 40 are extended through the leg 12 or the extension 34 thereof, the angle bar 32 and the angle lugs 38. Obviously, by extending the bolts 40 through a selected pair of the upper and lower apertures 36, the height of the forward portion 26 of the elongated bar 24 can be easily adjusted upon the chair. The preferred means of effecting this adjustment is further described in the patent to Nuberg 1,721,743 issued July 23, 1929.

A means is provided for retaining the rear inclined portion 28 of the elongated part 24 in adjusted positions upon the extension 18 of one of the rear legs 14 and this means will be described immediately hereinafter. As stated earlier, one of the rear legs 14 on the extension 18 is of angle construction and one flange 42 thereof is provided at the extended portion 18 with a plurality of vertically spaced slots 44. The free end of the rear portion 28 is provided with an angulated bifurcated portion 46, the furcations 46' and 46'' of which are adapted to extend through a pair of adjacent slots 44. The drawings illustrate four slots and consequently, it will be understood that three different vertically adjusted positions can be obtained as a result. It will be understood, however, that any number of vertically spaced slots may be appropriately provided.

As will be seen clearly from Figure 4 in particular, the construction of the rear portion 28 and the angulated bifurcated portion 46 is such that the desk arm brace can be secured in any

vertically adjusted position on the extension 18 of the rear leg 14 tightly and noiselessly. This is accomplished by bending the bifurcated portion to provide a portion 48, that is, substantially perpendicular to the longitudinal axis of the rear portion 28 of the elongated bar 24, and it is this portion 48 which extends through the slot 44. The portion 48 is again bent at right angles to provide a portion 50 which lies flat against and abuts the inner face 52 of the flange 42 so that when the brace is properly assembled in the slots, there will be no projections which might possibly damage the clothing of a person sitting in the chair. To insure a tight fit and prevent any substantial relative movement between the brace and the extended portion 18 of one of the rear legs 14, the bifurcated portion 46 is bent at a slightly outward angle as at 54 to the longitudinal axis of the rear portion 28 of the elongated bar 24. This produces an inwardly projecting portion 56 that bears against the outer face 58 of the flange 42 and produces a noiseless tight fit when the furcations are fully engaged in the pair of adjacent slots 44.

In view of the foregoing description taken in conjunction with the accompanying drawing it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. In a chair having front and rear legs, a seat member and a back member, said rear legs being extended to secure the back member; a desk arm brace comprising an elongated bar having a forward portion and a rear downwardly inclined portion integral therewith, said forward portion being adapted to secure a desk arm, means for securing said forward portion on one of said front legs in vertically adjusted positions and means for securing said rear portion on the ex-

tended portion of one of said rear legs in vertically adjusted positions, said last-named means including vertically spaced slots in said extended portion of said one rear leg, and an angulated bifurcated member at the free end of said rear portion having the furcations positioned in a selected pair of adjacent slots.

2. The combination of claim 1, wherein said one rear leg and extended portion are of angle 10 construction, said slots being provided in one flange of said extended portion, each furcation of said bifurcated member being bent to form a portion substantially perpendicular to the longitudinal axis of said rear portion of said bar and 15 extending through one of said slots and a further portion bent perpendicular to said first bent portion, said further portion lying flat against and abutting the inner face of said one flange.

3. The combination of claim 2, wherein said 20 bifurcated portion is disposed at a slight outward angle to the longitudinal axis of said rear portion to provide an inwardly projecting portion adapted to bear against the outer face of said one flange and maintain a tight engagement of 25 said furcations in said slots.

4. In combination with a chair having a front and a rear leg, a desk arm brace having a forward end adjustably secured to said front leg and a downwardly inclined portion adjustably secured to said rear leg, said rear leg having a plurality of spaced adjacent slots extending longitudinally thereof, a bifurcated end on said downwardly inclined portion of said brace, the furcations of said bifurcated end being laterally offset 35 from and parallel to said brace, said furcations being positioned in a selected pair of adjacent slots.

ARTHUR P. BRASHEAR, JR.
